UNITED STATES PATENT OFFICE.

FRANK OSCAR GUSTAFSON, OF BESSEMER TOWNSHIP, GOGEBIC COUNTY, MICHIGAN.

OVERHEAD-RAILROAD CONSTRUCTION.

1,112,446.

Specification of Letters Patent.

Patented Oct. 6, 1914.

Application filed July 27, 1914. Serial No. 853,549.

To all whom it may concern:

Be it known that I, FRANK OSCAR GUSTAFSON, a citizen of the United States, residing in Bessemer township, Ironton Location, 5 in the county of Gogebic and State of Michigan, have invented certain new and useful Improvements in Overhead-Railroad Construction, of which the following is a specification.

10 The present invention relates to overhead railroad construction, which has a single row of gauntlet posts and the object is to provide such railroads of simple construction using up as little ground space as possible.

15 The invention applies principally to coal and ore dumps, and from actual experience it has been proved that this construction lasts considerably longer than similar ones 20 known to the present time. Usually the dumping platforms and the overhead railroads have to be re-built as soon as the coal and ore has been removed from the ground, but the life of the present construction is 25 claimed to be 8 to 10 times longer than the old ones on account of its durability.

30 In the drawings, one embodiment of my invention has been illustrated, and, Figure 1 shows a transverse section of the device. Fig. 2 is a similar section in larger scale, 35 of the track and the central portion of the construction. Fig. 3 shows a supporting trestle. Fig. 4 is a longitudinal central section along line 4—4 Fig. 6. Fig. 5 is a horizontal section along line 5—5 of Fig. 4, and, Fig. 6 is the top plan view of Fig. 2.

35 The gauntlet posts which are plated at uniform distances to support the track and centrally therewith, each consists of a single 40 post 10 at its upper end provided with a T-piece 11 sustained by struts 12 which are bolted to the post and secured by means of strap bolts 35 to the T-pieces 11. The longitudinal ties or girders extend from one of 45 the gauntlet posts to the next, and are held together by wooden bed pieces or joining members 13 which rest directly on the T-pieces 11. This consists of girders comprising a wooden or metal beam 14 reinforced 50 by a tension member 19 preferably an inverted light rail with distance piece 21 in the middle. The ends of the tension member 19 are riveted to the connecting plate 20 which is bolted in a suitable manner to the 55 beam 14. The ends of the girders are also bolted to the joining members 13. A floor-

ing 15 is laid across the two ties or beams 14 and on top of this and parallel to the beams 14 are placed the rails 16 and near the latter the guard rails 17. As seen in Figs. 60 1 and 2 the weight of a passing train will then be symmetrically distributed over the posts 10. In order to make a still firmer construction, I provide supporting trestles 65 at suitable distance apart and connected with the gauntlet posts. Usually I do not provide these trestles for every post, but find them necessary where posts are strained to a great extent as for instance in curves and at the end of the line. These trestles have two 70 slanting legs 23 connected by suitable cross beams 24 and 25 secured by strap-bolts. Anchor pieces 29 driven into the ground on the outer side of the trestle, are connected with the top cross-beams 24 by means of 75 the suspension wires 28 with suitable tightening bolts in the anchor pieces 29.

On top of the T-pieces 11 are secured 80 hinged plates 30 with eyelets to which guy ropes 26 are attached. The other ends of the 85 guy ropes are provided with tensioning bolts 27 which are run through and secured in the cross-beam 25 which preferably is situated on the outer side of the trestle. Therefrom the guy ropes 26 run upwardly over the top 90 cross-beam 24 and on to the hinged plate 30.

Although the figures show a wooden construction I do not limit myself to that alone as the invention also relates to iron and steel construction built in a similar manner. 95

I claim:

1. An overhead railroad having longitudinal ties resting on a plurality of gauntlet posts; each longitudinal tie comprising a beam extending between two gauntlet 95 posts, a tension member suspended along the beam and connected thereto by a plate riveted to each end of the tension member and secured by bolts to the beam, and a compression member situated at its middle; 100 joining members connecting the ends of the beam and connecting the ends of the two beams, said joining members resting directly on the T-pieces.

2. An overhead railroad having longitudinal ties resting on a plurality of gauntlet posts; each gauntlet post comprising a single upright post and a T-piece secured at the top of said single post, diagonal struts connecting the ends of the T-pieces with 110 the single post, said longitudinal ties resting on top of said T-pieces; each longitudi-

nal tie comprising a beam extending between two gauntlet posts, a tension member suspended along the beam and connected thereto by a plate riveted to each end of 5 the tension member and secured by bolts to the beam, and compression members between the beam and the tension member situated at its middle; joining members connecting the ends of two beams, said joining members resting directly on the T-pieces.

3. An overhead railroad having longitudinal ties resting on a plurality of gauntlet posts; a trestle on each side of said gauntlet posts and at suitable distance 15 therefrom, and anchorage members for each trestle, and tensioning members between said trestle and said anchorage members, and other tension members secured to said gauntlet posts at one end and to the lower 20 part of the trestle at the other end, said other tensioning members passing over the top of the trestle.

4. An overhead railroad having longitudinal ties resting on a plurality of gauntlet posts; each gauntlet post comprising a 25

single upright post and a T-piece secured at the top of said single post, diagonal struts connecting the ends of the T-pieces with the single post, said longitudinal ties resting on top of said T-pieces; each longitudinal tie comprising a beam extending between two gauntlet posts, a tension bar suspended along the beam and connected thereto by a plate; a trestle on each side of 30 said gauntlet posts and at suitable distance 35 therefrom, and anchorage members for each trestle, and tensioning members between said trestle and said anchorage member, and other tensioning members secured to said gauntlet posts at one end and to the 40 lower part of the trestle at the other end, said other tensioning members passing over the top of the trestle.

In testimony whereof I affix my signature in presence of two witnesses.

FRANK OSCAR GUSTAFSON.
